Application October 10, 1946, Serial No. 702,520

6 Claims. (Cl. 120—32)

1

This invention relates to copyholders for use with typewriting machines and the like.

The principal object of the present invention is to provide an improved copyholder.

An object is to provide a copyholder which is more convenient to operate and more easily set by the operator of the machine when changing to different kinds of copy.

An object is to provide a copyholder which may be operated by foot power.

An object is to provide a copyholder which may be more easily and more accurately adjusted for line feeding purposes.

An object is to provide a copyholder which may be both operated and adjusted either manually or by foot power.

An object is to provide a copyholder in which the amount of feed of the copy may be accurately adjusted by direct reference to the copy through an auxiliary line finder.

An object is to provide a copyholder which is more adaptable to different kinds of copy.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a front elevation of the upper part of the copyholder.

Fig. 2 is a rear elevation of the copy holder.

Fig. 3 is a side elevation of the upper part of the copyholder as viewed from the right in Fig. 1.

Fig. 4 is a plan view of the treadle.

Fig. 5 is a side view of the treadle.

Fig. 6 is a detail view on the line 6—6 in Fig. 5.

Fig. 7 is a large scale detail view showing the line feed device in partly operated position.

Fig. 8 is a view similar to Fig. 7 but showing the line feeding device in released position.

The main framework of the copyholder is most clearly shown in Fig. 2 and comprises a flat base plate 10 to which are riveted or otherwise secured the vertical posts 11. Vertically slidably mounted in the posts 11 is the plate 12 composed of sheet metal having its edges formed with flanges 12a at right angles. For the purpose of guiding the plate 12 for vertical movement the bottom flange 12a is provided with holes to receive the posts 11 and the plate 12 has secured to it blocks 12b having holes through which pass the posts 11. The blocks 12b are provided with thumb screws 13 to permit the plate 12 to be adjusted up or down on the posts 11 to suit the operator's height.

Also secured to the plate 12 is a block 13a (Fig. 2) which acts as a socket for a dash pot tube 14, the lower end of which is held in place by a plug 12c secured to the lower flange 12a. Guided

2

in the block 13a and housed in the dash pot tube 14 is the feed rod 15, the lower end of which is provided with a cup-shaped piston packing 15a. The upper end of the rod 15 is also guided in a bushing 12d carried by the upper flange 12a of plate 12. The upper end of the rod 15 is secured in a block 16 fastened to the upper end of the copyholder plate 17.

Secured to the top of the copyholder plate 17 (Figs. 1 and 3) is a cross bar 18 formed with keyhole slots 18a at its ends in which is removably mounted the copy clamping bar 19, the ends of the bar being bent like the arms of a bail and provided with grooves fitting in the narrower portions of the keyhole slots 18a. Loosely slidably mounted on the clamping bar 19 are the clamps 20 which, as most clearly shown in Fig. 3, are formed somewhat like a cam with the high part of the cam slightly greater in radius than the distance from the center of the bar 19 to the surface of the cross bar 18.

Preferably the clamps 20 are made of some material like dense vulcanized rubber or a suitable plastic formed with grooves 20b (Figs. 1 and 3) which create double jaws for gripping a copy sheet 21 which may be inserted by placing the upper edge of the copy sheet a little below the clamps 20 and pushing upwardly. This movement, due to the friction between the clamps 20 and the paper, causes said clamps to be rocked slightly in a counterclockwise direction (Fig. 3) but as soon as the paper is released, the weight of the clamps 20 causes them to rock slightly clockwise and grip the paper.

For the purpose of line feeding the copyholder plate 17 and the copy sheet 21 supported on the face thereof, there is provided the mechanism shown in Figs. 2, 7, and 8. Under normal conditions the plate 17 is kept in an elevated position, to which it has been fed by the line feeding mechanism, by means of a pair of plates 22 which conveniently may be made of a material like a laminated plastic, such as "Bakelite" or "Formica." The plates 22 are provided with holes very slightly larger than the rod 15 and the left hand ends of the plates 22 normally rest on a stud 23 carried by the plate 12 while the right hand ends of the plates 22 are free. A double leaf spring 24 carried by a slotted pin 25 on the plate 12 has one of its fingers pressing on the top surface of the top plate 22 a little to the right of the center of pin 23, thereby tending to urge the plates 22 in a clockwise direction. Due to the small difference between the holes in the plates 22 and the diameter of the rod 15, the plates hold the rod 15 against downward movement in Fig. 2.

For the purpose of feeding the rod 15 upwardly there is provided a somewhat similar pair of plates 26, the left hand ends of which rest on a

feed plunger 27 and one of the fingers of the spring 24 presses on the top plate 26 to the right of the upper end of the feed plunger 27. Thus plates 26 likewise prevent the rod 15 from moving downwardly in Fig. 2. The rod 27 is guided at its upper end by a bracket 28 carried by the plate 12 and its lower end is pivotally connected to a hand lever 29 pivoted at 30 to the plate 12. The lever 29 is held in the position of Fig. 2 by means of a coil spring 31 which urges the lever 29 in a clockwise direction and which is attached at its upper end to a circular nut 32 on an adjusting screw 33 carried by the upper flange 12a. By turning screw 33 and holding the nut 32 against rotation the tension on the spring 31 may be 15 adjusted.

Upward movement of the rod 27 is limited by a Bowden wire 34, the sheath 35 of which is secured to the left hand flange 12a (Fig. 2) by means of the clamping blocks 36. The lever 29 is formed with a handle piece 29a by means of which the typist may operate the feed mechanism with the right hand.

The base plate 10 is narrow enough to be slipped underneath the average typewriter or, if desired, it may be large enough so that the typewriter may rest upon the plate and thereby hold the copyholder in place with the copyholder plate 17, and the copy sheet 21 thereon facing the typist from the back of the typewriter. It will be apparent that the operator may use the right hand to operate the lever 29 by pressing down on the finger piece 29a.

When the lever 29 is rocked counterclockwise in Fig. 2 the plunger 27 is drawn downwardly, thereby permitting the spring 24 to press the left hand ends of the plates 26 downwardly and causing said plates to follow the upper end of the plunger 27 to the position of Fig. 7. The relieving of the pressure of the upper end of the plunger 27 on the left hand ends of the plates 26 allows said plates to pivot slightly in a counterclockwise direction on the rod 15, thereby losing their grip on the rod 15 and permitting them to fall. However, when the lever 29 is released and restored by spring 31 to the position of Fig. 2, the plunger 27 will be pushed upwardly. Due to the fact that the spring 24 acts on plates 26 to the right of the plunger 27, said plates will now pivot in a clockwise direction on the end of the finger of spring 24, thereby causing the plates to grip the rod 15 firmly while plunger 27 is being raised. The spring 31 is made strong enough so as to be capable of raising the rod 15, the copyholder plate 17, and the copy sheet thereon an extent which is governed by the amount the plunger 27 has been drawn downwardly, either by the hand of the operator on the finger piece 29a or by a pull exerted downwardly by the Bowden wire 34. The latter, as will be made clear hereinafter, may be operated by means of a foot treadle, thereby relieving the typist of the necessity for actuating the lever 29 by hand, thus effecting a saving of time in performing a copy job and reducing hand motion by the operator.

The stroke of the lever 29 may be varied normally to suit the spacing of the lines of the copy. Adjustment of the amount of feed is determined by an adjustable stop block 37 (Figs. 1, 2, and 3) which is slidably mounted on a rod 38 secured to blocks 39 carried by the left hand flange 12a in Fig. 2. Interposed between the lower end of the stop block 37 and the lower block 39 is a relatively weak coil spring 40 which tends to elevate the block 37. The latter is provided with a thumb

screw 37a by means of which the block 37 may be clamped in any adjusted position along the rod 38. The block 37 also has formed therin a stop lug 37b which projects underneath the left hand end (Fig. 2) of the lever 29. Assuming the block 37 to be clamped to the rod 38 in the position shown in Fig. 2 it is apparent that the lever 29 may only be moved to the dotted line position, thereby permitting a relatively short vertical feed to be given the copyholder support plate 17.

After the typist has finished copying a page it is necessary that the support plate 17 be restored to the position of Fig. 2 and a new sheet 21 of copy inserted. Release of the copyholder is effected by the Bowden wire 41, the sheath 42 of which is clamped to the plate 12, adjacent the block 13, by means of the clamping blocks 43, similar to the blocks 36. When the Bowden wire 41 is pushed upwardly it engages the right hand end of the lowest plate 26 and rocks said plates to the horizontal position shown in Fig. 8. Owing to a long pin 26a on the topmost plate 26, the plates 22 are likewise rocked to a horizontal position. This relieves the grip which the plates 22 and 26 have on the rod 15 and allows the rod 15 and the plate 17 to drop. In order to prevent the plate 17 and parts connected thereto from falling with a slam, the lower end of the tube 14 is formed with a bleeder aperture 14a (Fig. 2) which permits the air trapped between the piston 15a and the plug 12c to escape rapidly but sufficiently slowly to cushion the fall of the rod 15 and the plate 17. The Bowden wire 41 also may be operated by a foot pedal in a manner which will be made clear hereinafter.

In order to enable the typist to follow the lines of copy more conveniently there is provided a line finder 44 (Figs. 1 and 3) which may take the form of a thin flat strip of transparent plastic on which may be scribed a horizontal line 44a which conveniently may be filled with red ink to make it clearly distinguishable from lines on the copy. The line finder 44 is attached to the upper end of a block 45 rotatably slidably mounted on the rod 38 between a collar 46 fixed on the rod and a spring 47, the upper end of which abuts the upper lug 39. As most clearly shown in Fig. 3, the collar 46 is transversely slotted to form a cam face 46a and the block 45 is shaped at its lower end to conform to the shape of the upper face of the collar 46. Owing to the combined effect of the weight of the block 45 and finder 44 and the spring 47, the finder 44 is held in a position parallel with the front face (Fig. 1) of the copyholder plate 17. However, the construction just described permits the finder 44 to be swung forwardly and to the right (Fig. 1) during the course of which the cam face 46a will cause the finder 44 to be cammed upwardly slightly against the compression of the spring 47, permitting copy sheets to be changed more conveniently.

Means is provided to enable the operator, either by hand or by foot, to adjust the feed of the copy to suit the line spacing of the material being copied. For this purpose there is secured to the rod 27 a cross bar 48 (Fig. 2) which extends across the back of the copyholder and is provided with forwardly projecting lugs 48a, 48b, which among other things serve to guide the plate 17 vertically by coacting with the edges of plate 12. Attached to the right hand lug 48b (Fig. 1) is a block 49 which conveniently may be made of plastic. This block is formed with a plurality of vertical bores arranged in a row, as most clearly

shown in Fig. 3, into any one of which may be received the round shank of a pivot member 50, the upper end of which is slotted to receive an index guide or auxiliary finder 51 preferably formed of transparent plastic material. The guide or finder 51 has a scribed line 51a of a contrasting color to the scribed line 44a which normally coincides horizontally with the line 44a but is shown in lowered or indexing position in Fig. 1 for convenience of illustration and to avoid confusion of lines between the finders 44 and 51.

The pivot member 50 is formed with a cam face 50a like the cam face 46a which cooperates with a rib 49a formed along the upper left hand corner of the block 49 (Fig. 1). Thus the auxiliary finder 51 normally tends to take the position shown in Fig. 1 slightly in front of the left hand end of the finder 44, but, like the latter, may be swung out of the way when it is desired to insert the copy. The pivot element 50 is merely loosely received in the hole in block 49 and may be shifted forwardly to different holes to accommodate different thicknesses of copy. Thus, if it is desired to copy something, the pages of which cannot be separated, the finder 44 may be swung out of the way and the auxiliary finder 51 may be moved forwardly to accommodate the thickness of the copy and used as a line finder. The manner in which this is done will be made clear hereinafter.

The Bowden wires 34, 41 are operated by foot power by means of the treadle mechanism shown in Figs. 4, 5 and 6. This mechanism includes a base plate 52, the underside of which may be faced with friction material 52a, such as soft rubber, to prevent slipping on the floor, since it would seldom be convenient or desirable to fasten the treadle mechanism to the floor. Secured to the top face of the plate 52 are the brackets 53 having the pivots 54 for the foot treadle 55, the latter being provided with suitable brackets 56 receiving the pivots 54. The treadle 55 is normally inclined as shown in Fig. 5 and is provided with a heel plate 57 which may be adjusted to accommodate the typist's foot. For this purpose the heel plate 57 is formed with the lugs 57a which are bent downwardly and to the right to enable the lugs to be inserted in holes 55a in the treadle 55. The left hand edge of the heel plate 57 is formed with a flange 57b to prevent the typist's foot from slipping down the treadle. By grasping this flange and lifting the plate 57 it may be rocked in a clockwise direction to disengage the lugs 57a from the holes with which they are registering and reinsert the lugs in a different pair of holes in a manner which will be obvious from the drawings.

For the purpose of operating the Bowden wire 34, the base plate 52 is formed with a bracket extension 52b (Fig. 6) having an offset lug to which is secured the sheath 35 of the Bowden wire 34. The latter is provided with an adjustable collar 34a which limits the extent to which the wire 34 is pulled into the sheath 35 (Fig. 6) by the tension of the spring 31 (Fig. 2) acting on the other end of the Bowden wire 34 through the lever 29. It is this collar 34a which limits the extent to which the plunger 27 moves upwardly upon release of the lever 29. The Bowden wire 34 is provided with a second collar 34b in engagement with a bracket extension 55b of treadle 55, the extension being forked to loosely receive the Bowden wire 34. It is evident that rocking of the treadle 55 in a clockwise direction (Fig. 5) will result in depression of the extension 55b, thereby transmit-

ting movement to the Bowden wire 34 in a direction to withdraw said wire from the sheath. This, of course, results in the other end of the Bowden wire 34 (Fig. 2) moving downwardly, operating the lever 29 and effecting the line spacing of the copy.

For the purpose of operating the Bowden wire 41 the base plate 52 is provided with a bracket 52c on which is pivoted at 52d a foot pedal 58 having the toe engaging surface 58a. The pedal 58 is pivotally connected at 58b to a collar 59 secured to a plunger 60 fastened to the Bowden wire 41. The sheath of the Bowden wire 42 is secured to a bracket 52e fixed to the base 52 and a spring 61 is interposed between the bracket 52e and the collar 59. When the pedal 58a is rocked clockwise by the typist's toe, the plunger 60 is pushed to the left (Fig. 5), thereby pushing the Bowden wire 41 upwardly out of its sheath 42 in Fig. 2 to release the plates 22, 28, as described above.

The copyholder may be operated in several different ways, depending upon the typist's preferences and upon the type of copying job involved. For copying ordinary typewriting where the lines are uniformly spaced on loose sheets, the typist, after placing the first copy sheet 21 in place under the clamps 20, will loosen the thumb screw 37a and then depress the lever 29a, either by the same hand as loosens the thumb screws 37a or by means of the treadle 55. In depressing the lever 29a by either method, it is moved slowly until the index line 51a on the auxiliary finder 51 reaches a position a little below the first line of typing as in Fig. 1, the sheet 21 being initially inserted so that the line 44a on the main finder 44 is a trifle below the first line to be copied. While holding the lever 29a depressed, the thumb screw 37a may be tightened. Owing to the action of the spring 40 the lug 37b will be held in contact with the lever 29a and moved therewith while the lever 29 is being operated to position the finder 51 as shown in Fig. 1. The tightening of the thumb screw 37a will fix the stroke of which the lever 29a is capable and thereby will limit the feed to one line space interval on the copy.

Preferably the setting of the stop 37 in the manner just described will come after the first line has been copied, as otherwise the adjustment which is so effected will cause the copy to be line-spaced one line and it is desirable that this not take place until after the first line has been copied. It is necessary that the first act be to position the first line in proper relation to the scribed line 44a as otherwise there will be difficulty in determining where to set the auxiliary finder 51. After writing the first line and setting the finder 51, the relaxation of pressure on the treadle 55 will cause the copyholder to be automatically indexed one line space to position the second line in cooperation with the scribed line 44a on the finder 44. After this, it is merely necessary at the end of each line to depress the treadle 55 or the finger piece 29a as far as it will go.

In copying matter in which the spacing is likely to be irregular and cannot be predetermined by setting the finder 51 in the manner described above, the thumb screw 37a will be left loose so that the block 37 is free to reciprocate vertically on the rod 38 and follow the lever 29. After copying each line the typist will merely press down on the treadle 55 or on the lever 29 until the finder 51a registers with the next line to be copied and release the treadle or the lever 29. This will cause the copy to be spaced in propor-

tion to the actual spacing and enables the operator to vary the amount the lines are indexed to suit variations in spacing on the copy sheet.

Since the auxiliary finder 51 always normally stops with the scribed line 51a in register with the line 44a which may be termed the "normal sighting line" it is possible to use the finder 51 to draw the eye to a line which must be copied in cases where the material to be copied is in bound form and cannot be separated. An illustration is legal papers which are ordinarily bound with ribbon in such fashion that they cannot be taken apart without destroying the legal value of the documents. Such documents are usually bound at the top and in copying them it is possible to swing the main finder 44 out of the way and insert the pivot element 50 of finder 51 in the nearest hole in the block 49 which will accommodate the thickness of the copy material. The block 37 may then be set in the manner described above where the spacing is uniform or the thumb screw may be left loose and the finder 51 moved downwardly variable distances to accommodate variations in the spacing of the copy. When the finder 51 is to be used in this manner, the copyholder may be provided with a third finder which is long enough to span the copy and the short finder may then be replaced by the longer finder.

One of the biggest advantages of the copyholder described above is the feature whereby the typist may instantaneously adjust the spacing to suit the copy by direct reference to the lines to be copied, making it unnecessary to make repeated adjustments in a screw or other device with which present copyholders rely upon for producing fine variations in the spacing or rely upon fixed adjusting devices limiting the feed to fixed line spacing increments which do not always coincide exactly to the line space of all typewritten material. This is important because of the fact that, according to the number of carbon copies made, the actual spacing on the ribbon copy, or first sheet may not be the same as the spacing of the carbon copy next to the platen. For example, when a large number of carbon copies are made, the outer sheet always has slightly greater line spacing than the innermost sheets owing to the difference in diameter of the pack of sheets and the platen. Commercial copyholders are not capable of accommodating such variations except by trial requiring the turning of a fine pitch screw stop which requires that at least several lines be typed before the spacing becomes accurate enough for the typist to rely upon it. With the arrangement disclosed herein the typist in one stroke can adjust the finder 51 to exactly the right line spacing.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a copyholder for typewriting and other office machines, a support, a copy carrier mounted on said support, a line finder mounted on said support, adjustable means for effecting a line-by-

line indexing movement of the carrier on said support and relative to said support, and an auxiliary line finder juxtaposed with the first line finder and movable on said support by said adjustable means to denote the extent of movement of said carrier when adjusting the adjustable means.

2. In a copyholder for typewriting and other office machines, a support, a copy carrier movable vertically on the support and having releasable means for holding a sheet of copy, a main line finder pivotally mounted on said support for movement in a horizontal plane from a copying position in front of the copy sheet to an inactive position permitting insertion of the copy sheet from in front of the copy carrier, means for indexing said carrier on said support relative to said finder, and an auxiliary finder movable on said support by said indexing means in a direction opposite the indexing movement of the carrier prior to indexing the carrier and in register with the next line to be copied, said auxiliary finder also being movable in a horizontal plane to an inactive position to permit insertion of the copy sheet.

3. A copyholder for typewriting and other office machines comprising a base plate, a support, means to adjustably movably mount said support on said base plate, a copy carrier movable on said support; a pair of line finders mounted on said support, one of said finders being normally stationary in register with a line to be copied, the other finder being movable to the next line to be copied, means for first moving said other finder to next line position and thereafter moving said carrier in a direction to bring said next line into register with the first finder, and means for setting the stroke of the moving means while said second finder is in next line position.

4. A copyholder for typewriters and other office machines comprising a support, a copy carrier mounted for indexing movement on said support, a line finder mounted on the support for following a line to be copied, and means for moving said carrier including a second finder movable by the moving means to coincide with the next line to be copied prior to moving the carrier to bring the next line into register with the first finder.

5. In a copyholder, a copy carrier, means operable to effect a line spacing movement of the copy carrier, and a pointer device movable over the copy on said carrier for visually predetermining the line spacing movement of the carrier, said device being operated by the first named means in advance of movement of the carrier.

6. In a copyholder, a copy carrier line indexing means including means variably settable to determine the amount of line spacing movement of the copy carrier, and a pointer device moving over said copy and actuated by the indexing means for determining the setting of the determining means by direct measurement of the copy.
